(57) **CLAIM**

The ornamental design for a massage gun as shown and
described.

DESCRIPTION

FIG. 1 is a top, front, right side perspective view of a
massage gun, showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom, rear, left side perspective view thereof.

The dashed broken lines in the drawing depict portions of
the massage gun that form no part of the claimed design.
